COMBINED STETHOSCOPE AND BINAURALS UNIT

Sylvan L. Hart, 545 West End Ave.,
New York, N.Y. 10024

Filed Apr. 11, 1973, Ser. No. 350,075

Term of patent 14 years

Int. Cl. D24—02
U.S. Cl. D83—12 R

FIG. 1 is a perspective view of the combined stethoscope and binaurals unit showing my new design; and
FIG. 2 is a front view of the binaurals system and a perspective view of the stethoscope shown in FIG. 1.

I claim:

The new, original and ornamental design for a combined stethoscope and binaurals unit, as shown and described.
